ROTARY DRILLING APPARATUS

Carroll L. Deely, Dallas, Tex.

Application January 5, 1940, Serial No. 312,590

7 Claims. (Cl. 255—19)

This invention relates to an improvement in rotary drilling apparatus, and more particularly to a combined rotary table and casing head.

In the usual system of power driven rotary apparatus, a rotary table is used to suspend a hollow drill stem carrying a drill bit, and rotation of the table imparts turning movement to the drill stem to accomplish the drilling operation. The drill stem operates in a well casing which is usually closed at the top by a casing head secured thereto and provided with a packing gland around the drill stem. This usually locates the rotary table above the casing head through which the drill stem operates, and the separate and spaced relation of the rotary table and casing head renders the construction unstable and insecure.

When a square or polygonal kelly is used in the rotary table, it has been necessary heretofore to provide for a rotary bearing within the casing head to permit turning movement of the kelly relative thereto, with packing to confine the liquid, but this has been found objectionable because of the frequent wearing out of the packing and the difficulty and expense of providing effective packing between the kelly and the head of the casing.

The object of this invention is to improve the construction of the rotary drilling apparatus by combining the rotary table and the head in one unit which is provided with a rotary sleeve that is power driven, is packed off effectively to prevent the leakage of fluid for use of either a round drill stem or a polygonal kelly, and which materially simplifies the construction of the rotary unit, reducing its cost, and eliminating to a substantial extent the wearing out of the packing of the drill stem or kelly.

This object is accomplished by the provision of a casing head attached to the usual well casing and upon which is mounted a housing. A sleeve is journaled in the housing and is power driven so as to rotate the drill stem or kelly supported thereby, and which sleeve has an effective packing between the same and the drill stem or kelly that packs off the casing head, preventing a leakage therefrom.

I have shown a preferred embodiment of the invention in the accompanying drawings, in which:

Fig. 1 is a vertical sectional view through the combined rotary and casing head;

Fig. 2 is a top plan view thereof;

Fig. 3 is a horizontal sectional view through a portion of the unit, on the line 3—3 of Fig. 1;

Fig. 4 is a side elevation of the rotary sleeve, removed; and

Fig. 5 is a transverse sectional view through a rotary sleeve for a polygonal kelly.

Fig. 1 shows the invention applied to a well casing designated generally by the numeral 1, within which a drill pipe or kelly 2 is operatively mounted; and in drilling at the bottom of the casing, the drill pipe 2 usually carries a drill bit thereon, the rotation of which accomplishes the drilling operation.

Attached to the upper end of the casing 1 is a casing head 3 which may be screw-threaded thereon for support by the casing. Superimposed on the casing head 3 is a housing 9 provided with downwardly extending legs 5 that embrace the casing head 3 and are provided with lateral flanges 6 seated thereon between upstanding ribs 7 on the upper face of the casing head, as shown in Fig. 3. The legs 5 are secured to the sides of the casing head by screws 8.

The housing 9 is provided with an internal chamber 10 adapted to be filled substantially full of lubricant or grease, and is closed at the top by a cover plate 11 secured thereto by screws 12.

Operatively mounted in anti-friction bearings 13, such as tapered roller bearings as shown, and which are mounted respectively in the bottom and top of the chamber 10, is a rotary sleeve 14, shown detached in Fig. 4, and provided with a hub 15 from which upper and lower reduced portions 16 and 17 respectively extend. The roller bearings 13 engage and support the sleeve 14 on opposite sides of the hub 15, forming end thrust bearings therefor, and journaling said sleeve for rotation in the housing 9.

A ring gear 18 surrounds the hub 15 in the chamber 10, and is securely bolted thereto at 19 for rotating the sleeve. The ring gear 18 meshes with a pinion 20 mounted on a stub drive shaft 21 extending laterally through a wall of the housing 4 and journaled in bearings 22 therein. The bearings 22 are assembled in a radial sleeve 23 extending into the wall of the housing 4 and attached thereto by bolts 24. The stub shaft 21 usually is driven by a sprocket wheel mounted thereon, as indicated in dotted lines by the numeral 25 in Fig. 1, operated from the usual rotary engine or drawworks, although it may also be provided with a universal joint, shown at 26, through which the stub shaft 21 is driven from a drive shaft 27 connected with the source of power, for rotating the same and turning the ring gear 18.

The upper sleeve portion 16 extends through

the anti-friction bearings 13 and through and above the housing cover 11. A rotary table 28 has a splined connection with the upper end of the reduced sleeve portion 16, the latter being provided with spline grooves 29 therein (Fig. 4) to interfit with grooves formed in the central opening in the table 28, providing a tight fit therebetween for rotating the table upon turning movement of the sleeve 14. The rotary table 28 is secured against axial displacement relative to the sleeve portion 16 by a locking screw 30 extending radially in the rotary table and engaging in an orifice 31 (Fig. 4) in the sleeve portion 16.

A depending annular rib 32 extends downward from the under side of the rotary table 28 and overlaps an upstanding annular rib 33 on the cover 11 of the housing, the rib 33 being provided with an oil seal 34 therein around the sleeve portion 16, which elements 32-34 form a labyrinth packing around the rotating sleeve, tending to prevent lubricant from escaping between the housing 9 and the rotary table 28, as well as to prevent the entrance of foreign matter, dirt, etc., into the lubricant chamber 10.

A slip bonnet 35 is seated upon the rotary table 28 and is secured thereto by the engagement of lugs 36 on the table in orifices 37 in the bonnet 35, to cause rotation of the bonnet with the rotary table. Pins 38 extend through the lugs 36 to prevent the separation of the parts. The slip bonnet 35 carries the usual slips 39 removably seated therein, and which slips engage and hold on the table, drill stem or kelly 2, while screwing or unscrewing the pipe connections.

The upper portion of the rotary sleeve 14 is provided with a recess 40 therein having a shoulder 41 at the lower end of the recess. A packing is fitted in the recess 40, preferably a rubber packing sleeve, as designated by the numeral 42, which fits the recess between the surrounding wall thereof and the periphery of the drill stem or kelly 2, and fitted at its lower end on the shoulder 41. The packing sleeve 42 is shown as of bellows shape, a conventional form, for effectively packing the opening in the rotary sleeve 14 around the drill stem, and to accommodate either a round tubing or a polygonal kelly, either of which may be employed. The packing sleeve 42 is held in compressed relation between the shoulder 41 and a spacing ring 43 that is engaged by a packing gland nut 44 screw-threaded into the upper end of the sleeve portion 16 for adjustment therein to provide the required pressure on the packing and prevent leakage therethrough around the drill stem.

The lower sleeve portion 17 extends downward through the housing 9 and the lower anti-friction bearing 13 in the bottom wall thereof, and through the casing head 3. An oil seal 45 surrounds the sleeve portion 17 beneath the lower anti-friction bearing 13 to prevent the leakage of lubricant from the chamber 10.

The lower end of the sleeve portion 17 is journaled in a bearing 46 fitted in the casing head 3 with a close fit between said bearing and sleeve tending to prevent the entrance of oil, mud, or foreign matter therebetween. The sleeve portion 17 is also surrounded by packing 47, confined by a packing gland 48 which is fitted to the upper portion of the casing head 3, being secured thereto by the usual screws 49. The packing gland 48 is capable of removal from the casing head and withdrawn between the legs 5 of the housing 9 for replacement of the packing 47.

The sleeve packing 42 may also be removed and replaced readily by removal of the packing gland nut 44 which then permits the withdrawal of the packing sleeve.

This combined rotary table and casing head is particularly adapted for the drilling in and cleaning out of wells where it may be desired to circulate fluid in either direction, for which purpose it is important that the casing head be effectively packed while permitting rotation of the drill stem or kelly relative thereto, and a fluid connection 50 is provided in a side of the casing head 3 for circulating fluid into or out of the casing.

As shown in Fig. 2, the housing 9 is provided with eyelets 51 on opposite sides of the drive shaft 21 for attaching the source of power or driving equipment to the housing and holding the parts in properly spaced and braced relation.

It will be obvious that the invention is used in the usual manner of operating rotary apparatus, whereby the drill stem or kelly 2 is supported on the rotary table 28 for rotation with the sleeve 14 as the latter is driven by the drive shaft 21. The unit combines the rotary table with the casing head for compactness of structure, and provides an effective packing relation between the drill stem or kelly and the rotary sleeve, avoiding undue wear on the packing, while accommodating a drill stem or kelly of different shapes, and yet effectively packing of the latter against leakage without undue expense.

Where a polygonal kelly is used, as indicated at 52 in Fig. 5, the axial opening 53 in the rotary sleeve section 17' should also be of polygonal shape, as shown, whereby longitudinal movement of the kelly is permitted while maintaining the driving connection therebetween.

It will be understood that a conventional drive bushing for a polygonal kelly may be substituted for the slips 39; and when a round drill stem is used, a friction drive may be substituted for the slips which will permit free longitudinal movement relative to the sleeve 14 while maintaining the rotary driving relation.

It is often desirable to use a rotary table for screwing or unscrewing drill stem joints. This is accomplished by rotating one joint of pipe while holding another. I have found that this action may be facilitated materially by an overload clutch within the drive system capable of disengagement when the torsion of the drive shaft exceeds a predetermined point. In this manner, the threads of the drill pipe are protected against shearing, and the pipe, from being damaged otherwise.

I claim:

1. In rotary drilling apparatus, the combination of a casing head adapted to be secured to a well casing, a housing, a sleeve journaled in the housing for turning movement relative thereto, means providing a fluid tight relation between said sleeve and the casing head, a rotary table mounted on the sleeve for turning movement therewith and having upstanding lugs thereon, means seated on the rotary table and detachably connected with the lugs for supporting a drilling member for turning movement therewith while extending through the sleeve into the casing, and means for providing a fluid tight relation between said sleeve and the drilling member.

2. In rotary drilling apparatus, the combination of a casing head adapted to be secured to a well casing, a housing supported on the casing head, and having a chamber therein, a sleeve

Journalized in the housing for turning movement relative thereto and having a depending sleeve portion extending into the casing head, means for providing a packing between said sleeve portion and the casing head, a rotary table carried by the sleeve and having upstanding lugs thereon, means for supporting a drilling member on the rotary table and detachably connected with the lugs for turning movement of the sleeve while said member extends through the casing head into the casing, and means for providing a fluid tight relation between the sleeve and said drilling member.

3. In rotary drilling apparatus, the combination of a casing head adapted to be secured to a well casing, a housing supported on the casing head, and having a chamber therein, a sleeve journaled in the housing for turning movement relative thereto and having a depending sleeve portion extending into the casing head, means within the housing for operating the sleeve, a rotary table having a splined connection with the upper end of the sleeve above said housing for turning movement therewith, a pin interconnecting the sleeve and table preventing relative axial movement, means for supporting a drilling member on said rotary table for turning movement with the sleeve, and means for providing a fluid tight relation between said sleeve and the drilling member.

4. In rotary drilling apparatus, the combination of a casing head adapted to be secured to a well casing, a housing having depending legs seated on the casing head for supporting the housing thereupon, said housing having a chamber therein, a sleeve extending through the housing and journaled in opposite sides of said chamber for turning movement relative thereto, said sleeve having a depending portion extending into the casing head, means forming a fluid tight relation between the casing head and said depending sleeve portion, bevel gearing enclosed in the housing chamber for rotating the sleeve, a drive shaft extending radially through the housing and connected with said bevel gearing for operating the same, a rotary table mounted on the upper end of said sleeve above the housing, and means supported on the rotary table for mounting a drilling member therein while said drilling member extends through the sleeve to the casing.

5. In rotary drilling apparatus, the combination of a casing head adapted to be secured to a well casing, a housing having depending legs seated on the casing head for supporting the housing thereupon, said housing having a chamber therein, a sleeve extending through the housing and journaled in opposite sides of said chamber for turning movement relative thereto, said sleeve having a depending portion extending into

the casing head, means forming a fluid tight relation between the casing head and said depending sleeve portion, gearing enclosed in the housing chamber for rotating the sleeve, a drive shaft extending laterally through the housing and connected with said gearing for operating the same, a rotary table mounted on the upper end of said sleeve above the housing, means supported on the rotary table for mounting a drilling member therein while said drilling member extends through the sleeve to the casing, said sleeve having a recess therein through which the drilling member is adapted to extend and open to one end of the sleeve, radially expansible packing means housed within said recess for providing a fluid tight relation between the drilling member and the sleeve and expansible for movement of the drilling member and connected parts therethrough, and means for confining the packing means therein.

6. In rotary drilling apparatus, the combination of a sleeve adapted to receive a drilling member therethrough, a housing enclosing said sleeve and having a top, said sleeve projecting upwardly through the top, a rotary table having a splined connection with the sleeve above the top, a pin extending radially of the sleeve and table detachably connecting the same together, and means for supporting the drilling member on the table.

7. In rotary drilling apparatus, the combination of a casing head structure adapted to be secured to a well casing, a drilling member extending therethrough with couplings thereon and adapted for rotation in the casing, a housing connected with the casing head structure and having a chamber therein, a sleeve extending through the housing and journaled in opposite sides of said chamber for turning movement relative thereto, said sleeve having a depending portion extending to the casing head structure, means for forming a substantially fluid tight relation between said casing head structure and said depending sleeve portion, gearing enclosed in the housing chamber and connected with the periphery of said sleeve for rotating the latter, a drive shaft extending through the housing and connected with the gearing for operating the same, a rotary device connected with the upper end of said sleeve above the housing, slip means carried by the rotary device for connecting the drilling member therewith while said drilling member extends through the sleeve, said sleeve having greater internal diameter from end to end thereof than the drilling member and couplings, and accordion-sleeve packing enclosed in the sleeve between the same and the drilling member for sliding movement of the drilling member and couplings therethrough.

CARROLL L. DEELY.
